UNITED STATES PATENT OFFICE.

ALEXANDER GERLACH, OF LAUTERBACH, GERMANY, ASSIGNOR TO DANIEL SCHANZ,
OF OBERSCHMITT, GERMANY.

VENTILATOR.

Original application filed July 5, 1927, Serial No. 203,325, and in Germany February 24, 1927. Divided
and this application filed May 26, 1928. Serial No. 280,910.

The present application is a division of my prior application Serial No. 203,325, filed July 5, 1927, and has reference to a ventilating device for buildings of the kind 5
5 composed of a frame having an outlet opening for foul air and an inlet opening for
fresh air.

The object of the present invention is to provide a novel form, construction and arrangement of parts for securing a thorough 10 discharge of foul air and supply of fresh air without producing a noticeable draft, while at the same time obtaining the admixture of a desirable proportion of warm air 15 with the indrawn cooler air in order to prevent undue reduction of temperature of the room in which the ventilator is arranged.

The invention consists of the features of construction, combination and arrangement 20 of parts, hereinafter fully described and claimed, reference being had to the accompanying drawing, in which:—

Fig. 1 is a front elevation of the improved ventilator.

Fig. 2 is a vertical front-to-rear section on line 2—2 of Fig. 1.

Fig. 3 is a horizontal section on line 3—3 of Fig. 1.

Fig. 4 is a perspective view of the 30 ventilator.

Fig. 5 is a similar view of a modified form of ventilator.

The ventilator comprises a box-like frame or casing *a*, of rectangular, oblong rectangular or other suitable form, open at front and rear and designed to be mounted in the wall 35 of a room near the ceiling.

The casing is subdivided by a partition *c* into an upper foul air exhaust opening *d* and a lower fresh air inlet opening *e*. The 40 partition *c* comprises two vertically disposed triangular shaped plates secured at their vertices to the rear of the casing adjacent to the side walls thereof and thence extending 45 forwardly in converging relation and having their basal edges abutting and united at the front of the casing. These plates form with the sides of the casing vertical channels *h* extending between the openings *d* and *e* whereby more or less of the outflowing warm 50 air may mix with the inflowing cool air, to temper the latter to a desirable degree without interfering with the exhaust of the major proportion of the foul air or the free

introduction of cool air. A grid *i* at the 55 front of the casing prevents the passage of solid particles into or through the ventilator.

Arranged at the upper front portion of the casing is a hood or wind-shield *g* consisting of an upper outwardly and downwardly sloping plate and a lower downwardly and inwardly sloping plate intersecting at their adjacent edges and forming triangular lateral passages *f*, above which and supported by the upper plate is a down-draft triangular passage *f'*, through which passages the foul air is drawn off from the room and into the opening *d* for discharge. The hood or wind-shield acts as a wind-break to prevent the too rapid exhaust of 70 warm air and by its air checking action to facilitate the admixture in the channels of a due proportion of warm air with the entering cool air. Efficient ventilation of a room without producing an objectionable draft 75 and without objectionably lowering the temperature of the room is thus assured.

In the modification shown in Fig. 5 there is provided, besides the upper hood *g*, an inverted V-shaped lower hood comprising 80 plates *k* and which overhangs the front of the opening below the hood *g* and acts as a baffle to prevent warm air from being drawn directly down into the cold air opening *e* and cold air from being sucked up into the 85 foul air opening *d*, so that undesirable commingling of the air currents will be prevented. This hood may, however, be provided with small openings *m* to allow currents of cold air to be drawn upward by suction and to promote the mixture of such 90 currents of cold air with the warmer air in the upper part of the room.

Having thus described my invention, I 95 claim:—

1. A ventilator comprising a casing open at front and rear, a V-shaped partition in said casing subdividing the same to form a lower cold air inlet, an upper warm air outlet and connecting passages between the same, and a hood at the upper front portion of the casing constructed to provide channels communicating with said warm air outlet. 100

2. A ventilator comprising a casing open at front and rear, a V-shaped partition in said casing subdividing the same to form a lower cold air inlet, an upper warm air outlet, 105

let and connecting passages between the same, a wind-shield at the upper front portion of the casing consisting of angularly related upper and lower plates forming lateral

5 air passages communicating with the warm air outlet, and a downdraft passage extending through the upper plate and communicating with the warm air passage.

3. A ventilator comprising a casing open 10 at front and rear, a partition in said casing subdividing the same into a lower cold air inlet and an upper warm air outlet, a wind-shield at the upper front portion of the casing providing passages communicating with the warm air outlet, and an inverted V-

shaped hood below said wind-shield overhanging the front of the cold air opening and having a plurality of small openings therein.

4. A ventilator of the type described in 20 claim 1 wherein the V-shaped partition consists of two triangular plates having their vertices secured at the rear of the casing adjacent to the side walls thereof, said plates extending forwardly in converging relation 25 and having their basal edges intersecting and united at the front of the casing.

In testimony whereof I have affixed my signature.

ALEXANDER GERLACH.
